UNITED STATES PATENT OFFICE.

GEORGE W. MATTERN, OF DAYTON, OHIO, ASSIGNOR TO THE CRAWFORD, McGREGOR AND CANBY COMPANY, OF DAYTON, OHIO, A CORPORATION OF OHIO.

GOLF CLUB.

Application filed May 15, 1922. Serial No. 560,931.

My invention relates to golf clubs and more particularly to clubs provided with metallic or other non-wood handle shafts.

The purpose of the invention is to afford 5 to such handle shafts of metal, composition or other shafts employed as substitutes for the standard wooden shafts, the peculiar characteristics, reactions and "feel" inherent in the natural wood shafts.

10 Golf club shafts of tapered metallic tubing are at the present time coming into use as substitutes of the natural wooden shafts usually constructed from seasoned hickory. Such metallic tubular shaft possess certain 15 desirable characteristics being non-breakable and being substantially unaffected by climatic, temperature and humidity conditions.

While such metallic shafts possess a reasonable degree of flexibility or bending moment, they are to a very great degree, if not 20 entirely, unresponsive to torsional strains. In this they differ very materially from the natural wood shafts. They also have the characteristics of transmitting to the player's hand excessive vibration, which by reaction upon the nerves frequently causes 25 numbness or in the absence of numbness, effects a disagreeable sensation. This tendency to conduct excessive vibration together with the unresponsiveness to torsional strain, 30 subjects the player's wrists to abnormal stresses and strains, which results in undue fatigue, and interferes with the player's stroke. Moreover, the rigidity of such metallic shafts induces an inharmonious action 35 of the club as a whole, destroys the "balance" of the club, and eliminates the characteristic "feel" which the skilled player prefers to experience and which to a great extent determines the quality of his playing.

When such tubular metallic shafts were first adopted for golf clubs, it was thought that responsiveness to torsional strain in the wooden shafts was objectionable and it was 45 sought to overcome this objection by the introduction of the tubular steel shaft. However, experience has demonstrated that responsiveness to torsional strain is a highly desirable characteristic as is also the damping 50 of excessive vibration before they reach the player's hands. Notwithstanding the inherent good features and desirable characteristics to be found in a tubular metallic golf club shaft, the inherent objectionable 55 characteristics have been so widely recog-

nized that the recognized officials of the golf association have promulgated rules prohibiting the use of metallic or other artificial shafts as substitutes for the natural wood shafts in official games and tournaments. 60

In the present instance the desirable characteristics of the tubular metallic golf club shafts are retained, and its undesirable features overcome by combining with the metallic shaft a second non-metallic section, which 65 will be amply responsive to torsional strain and which will absorb or dampen excessive vibration.

It will thus be seen that the invention pertains to a golf club, whether a driver, a 70 brassie, a mid-iron, a putter or other form of golf club, provided with a wood substitute shaft preferably though not necessarily of tubular form, but which is responsive to torsional strain and of comparatively low vi- 75 bration conductivity.

While the preferred construction is that of a tempered tubular steel section, it will be understood that other material of non-wooden character may be employed so long 80 as the finished shaft possesses the characteristics of responsiveness to torsional strain. In the accompanying drawing, Fig. 1 is a general view of a golf club in which the present invention has been embodied. Fig. 85 2 is a detail sectional view of a portion of a golf club handle shaft showing the interconnection and relation of the metallic and non-metallic sections. Fig. 3 is a similar view showing relative modification of proportion of the respective metallic and non-metallic sections, whereby varying degrees 90 of responsiveness to torsional strain or variations of conductivity of vibrations may be achieved. Fig. 4 is an end view of a club 95 handle shaft, illustrating relative arrangement of the grain in a wooden handle section in relation with the line of impact or striking face of the club head, to likewise vary the torsional response of the head. 100 Fig. 5 is a sectional view of a portion of a tubular shaft packed or filled to control vibration and the bending moment.

Like parts are indicated by similar characters of reference throughout the several 105 views.

In the accompanying drawings, 1 is the golf club head, 2 the handle shaft and 3 the hand grip. In this instance, the club shown in a driver or a brassie. It is to be under- 110

stood, however, that the invention is equally applicable to clubs of other types. In the present instance, the head 1, is usually and preferably made of wood. The handle shaft 5 comprises an initial section 4 of a wood substitute. This wood substitute may be fiber, composition or other material, preferably of metallic character, the preferred form being a tapered metallic tube. This metallic or 10 other wood substitute section terminates at a mid length point, preferably though not necessarily somewhat nearer to the handle grip 3 than to the head 1. In some cases, this substitute section may extend within 15 the handle grip. Connected to the wood substitute section, whether of metallic character or of other suitable material is a handle section 5, preferably of wood, but which may be of material having similar inherent 20 siliency, responsiveness to torsional stress and the quality of absorbing or dampening to some extent, excessive vibration. While various modes of attaching the shaft section 4 with the wood substitute section 3, may be 25 employed, the preferred form is to reduce the extremity of the handle section to an extended tenon thereon, which will be driven tightly within the open end of the tubular section 4. The relative proportions of the 30 wooden substitute or metallic section 4 and the handle section 5, will determine the inherent characteristics of the resultant handle shaft. By making the wooden handle section 5 of greater or less length, the degree of 35 responsiveness to torsional strain and to vibration may be varied, to meet the requirements and preference of different players. Likewise these may be varied to some extent by varying the length of the tenon 6, and 40 the distance to which it extends within the tubular portion 4. As a further modification to vary the inherent vibratory characteristics and bending moment of the handle shaft, the tubular section may be completely 45 filled by extending the tenon 6 therethrough, or it may be packed or filled throughout with material of more or less density, according to the characteristics desired to be produced. Such a filled tubular shaft section is shown 50 at 7, Fig. 5.

The wrapping of the handle grip may be confined entirely to the handle section 5, or it may be extended therebeyond onto the wood substitute section 4, depending upon 55 the relative length of the respective sections. The sections may be interconnected by any suitable means as for instance by pinning, by means of screw threads, or merely by a tight driving fit of the handle section within 60 the tubular section. However, cement is preferably though not necessarily, applied to the tenon before driving it into the tubular section.

Not only will the composite handle shaft 65 thus produced, imitate with great similarity

the inherent characteristics of a natural wood handle shaft, be responsive to torsional strain, or stress and absorbent of excessive vibration, but it will also obviate breakage of the club head to which a golf 70 club fitted with the usual form of steel or other metallic shaft are subject. The resistance of the metallic shaft as commonly employed to torsional stress subjects the head to excessive strain and many clubs are 75 broken, by the neck of the head 1 being fractured or split, due to the unresponsiveness of the shaft to the impact with the ball.

While it is true that an all metallic shaft 80 possessing torsional resistance may enable a player to drive somewhat more accurately, and obviate "slicing," such advantage is due solely to the mechanical qualities of the club, and gives the player an advantage which is not recognized as being sportsman-like. The 85 wooden handle shafts being the traditional and standard golf club handle shaft is reproduced in all of its desirable characteristics by the artificial substitute heretofore 90 described.

Hickory wood of the proper quality for 95 handle shafts is becoming quite scarce. Only a small portion of the hickory growth, that is the middle-zone portion is suitable for making golf club shafts. The sap wood, although possessing considerable strength, is elastic and being quite supple cannot be satisfactorily employed and hence there is a great deal of waste. While this wood is not 100 suitable for making the entire shaft, where it must be reduced to comparatively small diameter, it may nevertheless be satisfactorily employed in the present construction. In the present instance, it is employed in 105 pieces of much larger diameter and the looseness of the fiber or lack of density, which renders it objectionable for the entire shaft makes it especially desirable for the present purpose, wherein the response to torsional strain is to be found primarily in the 110 wood handle section. This soft wood or coarse grained material unsuited for the main portion of the shaft, also serves well 115 as an absorber of vibration.

The entire handle shaft may be made of 120 this soft wood or coarse grain hickory, or even other woods wholly unsuitable for golf club shafts may be employed, if encased in a length of reinforcing tubing, as shown in Fig. 5. While this casing or reinforcement 125 tubing is preferably metallic, it might be fiber, composition or even paper. In the event that the handle tenon 6 does not extend entirely through the tubular section 4 as shown in Figs. 2 and 3, the tubular section 130 may be packed or filled with suitable material to control the vibration and also the "whip" or bending moment. This packing or filling material may be of various forms. Ground cork, asbestos, fiber or other mate- 135

rial pressed into the tube under varying degrees of pressure or composition, wax or other material of different densities may be employed in a tube to regulate the vibratory characteristics, and degree of "whip." By reinforcing the tubular section by either the wooden insert or by filling it with materials as aforementioned, the thickness or gage of the material employed for the tube may be materially decreased thereby not only reducing weight of the shaft, but also economizing the cost of manufacture.

The responsiveness of the handle shaft to strains and stress may be further regulated by using care with regard to the relation of the grain or growth circles of the wooden handle section, with the line of the impact. In Fig. 4 of the drawing, which shows an end view of the golf club shaft, the grain or growth circles are shown substantially in line with the line of impact. The general direction of these variations of the wood being indicated by the line *a—a*. By turning the wood handle section through a quarter rotation so that the growth circles or markings of the grain agree substantially with the line *b—b* a different effect is attained. Between these extremities various intermediate effects may be had by turning the grain or course circles to various angles in relation with the line of impact, as for instance as indicated by the line *c—c*.

By the various means heretofore described, a wide range of variation or modification of characteristics may be had in close imitation of effects produced by the usual and traditional all hickory shaft.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect and the invention is therefore claimed in any of its forms or modifications within the legitimate and valid scope of the appended claims.

Having thus described my invention, I claim:

1. A golf club including a head portion, a tubular flexible non fibrous shaft and a fibrous handle section forming a continuation of said shaft formed independent of

and subsequently attached to said head portion and capable of limited twisting action.

2. A golf club provided with a shaft of metallic tubing and a wooden handle section connected to and extending beyond said shaft.

3. A golf club provided with a tubular metallic shaft and a handle extension of material possessing less resistance to torsional strain than said metallic tubing connected therewith rendering said shaft unit responsive to torsional strain.

4. A golf club including a head portion, a shaft including a tubular metallic section attached to said head portion and means additional to said metallic section whereby said club is rendered responsive to torsional strains irrespective of the torsional response of the tubular section, substantially as specified.

5. A golf club, including a tubular flexible shaft section highly resistant to torsional strains, to which the club head is attached, and a continuing section of characteristically different material responsive to torsional strains upon the shaft, independent of the response of the tubular section, and a handle grip carried by the last mentioned section.

6. A golf club provided with a shaft including a tubular section highly resistant to torsional strain joined to the head of the club and a handle grip section responsive to such torsional strain said sections being joined end to end, and extending axially one beyond the other.

7. A golf club provided with a tubular metallic shaft formed independent of the club head and means independent of the metallic shaft whereby the club will be responsive to torsional strains.

8. A golf club, a head portion and an independently formed tubular metallic shaft joined to the club head and a non-metallic section joined to such metallic shaft for intercepting the vibrations of said shaft before reaching the player's hands.

9. A golf club, a head portion and an independently formed tubular metallic shaft or the like joined to the club head and a non-metallic section joined to and projecting axially beyond the metallic shaft for dampening the vibrations induced in said metallic shaft.

10. A golf club, a head portion and an independently formed tubular metallic shaft or the like joined to the club head and a handle section of resilient material joined to said shaft extending therebeyond and forming a continuation thereof adapted to render the club responsive to torsional strains.

11. A golf club handle shaft comprising a tapered tubular metallic section and a wooden handle section fixedly connected to one end of the tubular section the said

wooden handle section forming a continuation of the tubular metallic section and extending beyond the terminal of the metallic section in axial alinement therewith.

5 12. A golf club handle shaft, comprising a tubular metallic section, a handle grip spaced away from the extremity of the metallic section and a longitudinally disposed wooden section, interconnecting the

grip and tubular metallic section in lineal 10 continuation of both the handle grip and metallic sections and serving to couple said longitudinally spaced portions one to the other.

In testimony whereof, I have hereunto set 15 my hand this 9th day of May A. D. 1922.

GEORGE W. MATTERN.
